UNITED STATES PATENT OFFICE.

ARCHIBALD S. NAPIER, OF ST. PAUL, MINNESOTA, ASSIGNOR TO J. N. COLLINS COMPANY, OF MINNEAPOLIS, MINNESOTA, A CORPORATION OF MINNESOTA.

ADVERTISING AND DISPLAY CARTON.

Application filed June 12, 1925. Serial No. 36,624.

The object of my invention is to provide a carton of the form generally used as a container for confections and the like, folded or fashioned in a way to simulate a filled 5 carton so that when placed in a show window or on a counter for display or advertising purposes, the carton will bear such a close resemblance to a filled article or package that the casual observer will not notice the 10 difference, and it will be unnecessary therefore to expose cartons filled with the article to be sold and subject the contents to the deteriorating effect of air and light.

A further object is to provide a display 15 carton of simple, inexpensive construction which will be economical in the use of material and render it unnecessary to use a considerable portion of the stock for advertising or display purposes, as usually is the case 20 when a carton actually filled with the goods to be sold is exposed on a counter or in a show window.

Other objects of the invention will appear 25 from the following detailed description.

In the accompanying drawings forming part of this specification,

Figure 1 is a view of a blank cut and scored to form the carton;

Figure 2 is a perspective view showing the 30 carton partially folded;

Figure 3 is a similar view showing a later step in the folding operation;

Figure 4 is a perspective view showing the final step of the folding operation; and

Figure 5 is a perspective view showing the carton completely folded and ready for exhibition or display purposes.

In the drawings, 2 represents the side panels of the carton having end flaps 3 and 3^a thereon. A bottom panel 4 is provided on the longitudinal edge of one of the side panels 2 and has a longitudinal parting flap or tongue 5 thereon. The side panels 2 are united by a top panel 6 and this panel is 40 scored lengthwise at 7 near the side panels 2 and parallel therewith to form a narrow extension 8 of the top panel, and when this panel is folded along the score lines 7 the extensions 8 will be at right angles substantially to the top panels and form continuations substantially of the vertical side walls 2 of the carton, thereby raising the top panel a considerable distance above the upper edges of the side walls of the carton. The top 45 panel and the extensions thereof have parallel

parallel lines or marks 9 thereon dividing the panel transversely so that the portion of the carton extending above the side walls will represent or have the appearance of a series of flat articles, such as pieces of confection 60 inserted into the carton and extending above its walls to a display or advertising position. The top panel and its extensions may, and usually will be, in some contrasting color to that of the carton walls representing a 65 wrapper by which the confection is covered and protected. The carton and the representation of the articles to be vended therein may, of course, be of any suitable color, depending upon the fancy of the manufacturer 70 and the character of the article to be displayed.

The ends of the top panel have flaps thereon scored transversely at 10, 11 and 12 to form panels 13, 14 and 15, and end flaps 75 16. The panels 13 are wider than the panels 14, as shown in Figure 1, and the inner portion of the panels 13 are suitably lined or marked to represent the wrapper of the articles in the carton, the width of the 80 space so marked being preferably a little wider than the vertical extensions of the top panel and when the panels 14 are folded upon the score lines 10 to conceal the outer portions of the panels 13, the inner portions 85 of said panels 13 will project above the folds at 11 and form right angle continuations of the vertical extensions 6 at the ends of the carton. When this fold has been made in the end flaps, the flaps 3 and 3^a are folded 90 together as indicated in Figure 4 and the panel 15 is folded down outside of these flaps and the tongue 16 inserted under the flaps to complete the folding of the carton.

The purpose of making the folds in the 95 end flaps at 10 and 11 is to provide gaps between the panels 14 and the end panels 13 so that the panels 13 will represent the ends of the row of articles in the carton raised above its walls and the panels 14 and 15 will represent the ends of the carton itself. This gap or space will expose the ends of the row of articles and cause the carton to more nearly resemble one that is actually filled with the 100 articles.

To support and strengthen the exposed upper portions of the panels 13, I may provide tongues 17 adapted to fold inwardly under the panels 13 as indicated by the dotted lines in Figure 2.

The carton may be made in various sizes according to the quantity or value of the articles to be displayed. Generally the device would be used to display or advertise flat rectangular pieces of candy, each enclosed in a suitable wrapper but I do not confine myself to the advertising or display of candy as the carton may be used as a display for other articles or to imitate articles which the merchant may not care to actually expose in his show windows or on counters.

I claim as my invention:

1. A display carton comprising a blank 15 scored to form side panels, having end flaps, one of said panels having a bottom panel thereon provided with a side flap, a top panel connecting said side panels and scored and folded lengthwise to form narrow angular 20 extensions of said top panel in the plane substantially of said side panels, said top panel and said extensions being lined or marked to represent a series of articles placed side by side and extending above the side walls 25 of the carton, said top panel having end flaps scored and folded to form end panels to interlock with the flaps of said side walls.
2. A display carton comprising a blank 30 scored and folded to form side and bottom panels and a top panel raised above the level of said side panels and marked or lined to indicate a series of flat articles placed side by side in the carton, said side panels having end flaps and said top panel having end flaps 35 folded to form inner and outer panels, the inner panels representing the walls of the articles in the carton and projecting above the outer panels and spaced therefrom, and said outer panels being folded over the flaps 40 of said end walls and having tongues to interlock therewith.

3. A display carton comprising a bottom and side panels, a top panel fashioned to represent a row of articles to be displayed and projecting above said side panels, and 45 end panels on a level substantially with said side panels and having gaps formed between them and the ends of the top panel for the purpose specified.

4. A device of the class described, comprising a top panel, two side panels, and a bottom panel, arranged to form four sides of a box, said carton having flaps overlappalable at the end of the box, said top panel and a portion of each side panel adjacent 55 said top panel being of less length than said side panels, said top panel having end-forming flaps each folded upon itself, to form a two-ply spacer portion, each flap having an extension beyond the folded portion adapted 60 for disposal at the outer side of the end of the box, and having a terminal tucking flap, for securing all flaps in end-forming position.

5. A device of the class described, comprising a top section, two side sections, and a bottom section arranged and foldable to form a box, said top section and a portion of each side section adjacent the top section being of less length than the side sections, to inset the top and portions of the sides at the ends of the box, end-forming flaps for the top section, each folded and providing a two-ply end-forming section, and further providing a single-ply auxiliary end-forming 75 section, having a terminal tucking flap, said carton having additional flaps adapted to be secured in end-forming position by the flaps of the top section.

In witness whereof, I have hereunto set my hand this 9th day of June, 1925.

ARCHIBALD S. NAPIER.
